CARTON

Reynolds Guyer, St. Paul, Minn., assignor to
Waldorf Paper Products Company, St. Paul,
Minn., a corporation of Minnesota

Application September 12, 1938, Serial No. 229,402

5 Claims. (Cl. 229—51)

My invention relates to cartons and particularly to reclosing cartons of the type in which an end wall of the same is constructed by means of end wall sections issuing from the lateral walls and secured together in overlying position.

An object of the invention resides in constructing the carton in a manner to form a closure adapted to be readily opened and reclosed.

Another object of the invention resides in providing a construction in which the closure is detachably secured to one or more of the lateral walls of the carton and in which detachment of the closure from the lateral walls is readily procured.

Another object of the invention resides in constructing one of the lateral walls with a line of weakening defining a tab at the upper portion of the same connected with the end wall section issuing therefrom and adapted to be removed from said lateral wall to leave a finger opening in said lateral wall.

A still further object of the invention resides in constructing the carton with a flap issuing from the end wall section of the opposite wall and adapted to be disposed beneath said tab.

Another object of the invention resides in constructing the flap with a line of weakening defining a tab adapted to register with the tab in the lateral wall of the carton.

A feature of the invention resides in arranging the parts so that said flap may be inserted into the carton adjacent the innermost surface of the wall with the opening, for the purpose of reclosing the carton, whereby the flap may be readily engaged through the finger opening in said wall for the purpose of opening the carton.

Another object of the invention resides in forming the other two end wall sections with transverse lines of weakening by means of which the same are formed with flanges disposed along the upper edge of the lateral walls from which they issue when the said sections are severed along said lines of weakening whereby buckling of the carton is prevented after the same has been opened and effective reclosing of the carton procured.

Other objects of the invention reside in the novel combination and arrangement of parts and in the details of construction hereinafter illustrated and/or described.

In the drawing:

Fig. 1 is a perspective view of a carton illustrating an embodiment of my invention and showing the carton prior to detachment of the closure.

Fig. 2 is a developed view of the blank from which the carton shown in Fig. 1 is constructed.

Fig. 3 is a perspective view of the upper end of the carton shown in Fig. 1 with the end sections arranged prior to attachment, said view being drawn to a larger scale.

Fig. 4 is a fragmentary view similar to Fig. 3 showing some of the sections secured together and viewed from the opposite side of the carton.

Fig. 5 is a fragmentary sectional view taken on line 5—5 of Fig. 1.

In reclosing cartons where the closure or end wall is attached to the body of the carton proper and forms a part thereof and is severed through lines of weakening, considerable inconvenience is encountered in being unable to readily sever the portions from one another to free the closure. The present invention provides a construction whereby this disadvantage is eliminated and by means of which the user may, by simple manipulation, free the closure for immediate use.

In the drawing I have illustrated a carton 10 which is constructed from a blank 12 of cardboard or some other similar material, which blank 12 is best shown in Fig. 2. This blank is formed with two longitudinal scores 13 and 14 which extend throughout the length of the blank. The blank 12 is further formed with a number of transverse scores 15, 16, 17 and 18 which together with scores 13 and 14 form in the blank a front wall 21, a rear wall 22 and side walls 23 and 24 which constitute the lateral walls of the carton. The marginal portions of the blank 12, outwardly of the scores 13 and 14, are slit along lines 25 and 26 which divide the portions of the carton outwardly of said scores into upper end wall sections 27, 28, 29 and 30 and lower end wall sections 31, 32, 33 and 34. In addition, a flap 36 is formed on the side wall section 23 which 40 is attached to the rear wall 22 forming a tubular structure adapted to be collapsed or extended. The end wall section 28 is of a width equal to or less than the depth of the carton from back to front, while the sections 27 and 29 are of a 45 width less than the width of the carton. Section 30 is, however, of a depth greater than the depth of the carton and is formed with a score 36 parallel to the score 13 which forms a flap 37 at the marginal portion of the section 30. The score 36 is disposed a distance from the score 13 equal to the depth of the carton so that the flap 37 is disposed in the plane of the front wall 21 when the sections are arranged to form a closure for the carton.

55 The front wall 23 of the carton is constructed

with two lines of weakening 38 and 39 which extend along the score 13 toward each other from the scores 16 and 17 and which fall short of one another at their inner ends. Between the inner ends of these lines of weakening is formed a crescent shaped line of weakening 41 which is disposed in the front wall 21 and which forms a tab 42 hingedly connected at 43 to the end wall section 28 through the score 13. In addition the two end wall sections 27 and 29 are formed with lines of weakening 44 which provide flanges 45 at the upper marginal portions of the side walls 23 and 24 which are hingedly connected to said side walls through the score 13. The flap 37, similar to the lateral wall 21, is formed with a crescent shaped line of weakening 46 terminating at the score line 36. This line of weakening defines a tab 48 hingedly connected at 47 through the score 36 to the lateral wall 30. The tab 48 is of the same form and dimensions as the tab 42 and is so situated that the same underlies the tab 42 and registers therewith when the end wall sections of the carton are assembled.

In the construction of the cartons the flap 36 is glued to the wall 22 at the factory to provide a tubular wall structure which comes collapsed. When the carton is to be erected at the locality of use, glue is applied to the inner surface of the end wall section 30 and the inner surface of the end wall section 28 or instead of the inner surface of the end wall section 30 to the outer surfaces of the end wall sections 27 and 29. In either event glue is omitted from the flap 37. The two end wall sections 27 and 29 are first folded inwardly and the end wall section 30 next folded upon the first named end wall sections and the flap 37 tucked in between the sections 27 and 29 and the lateral wall 21. This causes the tab 48 to underlie the tab 42 and to register therewith. Thereafter the end wall section 28 is folded upon the section 30 and the parts then pressed together. In the coating of the various surfaces, it is preferable that the flanges 45 or the opposite portions of the end wall section 30 be not coated with glue. The glued end wall sections 27, 28, 29 and 30 within the limits defined by the lines of weakening 38, 39, 41 and 44 and the score 13 define a closure for the carton which I have referred to by the reference numeral 40. After the upper end of the carton has been glued, the carton is filled and the lower end closed by gluing and folding over the end wall sections 31, 32, 33 and 34 in the customary manner. Thereafter a wrapper which has not been shown in the drawing may be placed about the entire carton. The carton is now ready to be distributed for use.

In the use of my invention, the entire wrapper or the upper end thereof is first removed from the carton. Pressure is next applied by the thumb to the tab 42 which, due to the lines of weakening 41 and 46 causes both tabs 42 and 48 to be severed from the structures to which they are attached and to be forced into the interior of the carton as shown in full lines in Fig. 5. This leaves an opening 50 in the front wall 21. Once these tabs have been freed the same may be pressed upwardly against the closure 40 whereupon it becomes a relatively simple matter to apply outward pressure to the closure 40. This causes the end wall section 28 to become severed from the front wall 21 along the lines of weakening 38 and 39. Further pressure causes the closure 40 to become severed along the lines of weakening 44 whereupon the entire closure may be swung rearwardly 75

along the score 13 as a hinge. The entire top of the carton is now open with the exception of the space occupied by the flanges 45 and access to the interior of the carton may be had. When it becomes desirable to reclose the carton, the flap 37 is held at right angles to the section 30 and inserted within the upper portion of the front wall 21. The arrangement of parts, after this has been performed is the same as when the carton is first assembled and is shown in Fig. 1. In so inserting the flap 37 the same is forced in between the ends of the flanges 45 and the front wall 21, said flanges urging the said flap into engagement with the front wall 21, thereby holding the closure in closed position. When it becomes desirable to re-open the carton, the closure 40 may be engaged by inserting the thumb through the opening 56 formed by removing the tab 42, whereupon the flap 37 may be engaged and the closure 40 again disengaged from the carton and swung backwardly upon the score 13 as a hinge.

The advantages of my invention are manifest. Cartons constructed in accordance with my invention completely enclose the contents thereof and have identically the same form and appearance as cartons now used for the purpose. By merely pressing the tabs inwardly into the carton, severance of the closure is readily started and thereafter the closure may be easily freed from the carton proper. The method of using my invention is readily apparent from the structure itself so that the user may avail himself of the advantages of the invention without the necessity of elaborate instructions.

Changes in the specific form of my invention, as herein disclosed, may be made within the scope of what is claimed without departing from the spirit of my invention.

Having described my invention, what I claim as new and desire to protect by Letters Patent is:

1. A carton constructed from sheet material and comprising lateral walls, a bottom connected with said lateral walls, end wall sections issuing outwardly from the ends of said lateral walls and being adapted to be folded over and secured together to form an end wall for the upper end of the carton, said carton being weakened to form a closure embodied in said end wall and severable from the carton, a flap formed on the end wall section issuing from one of the lateral walls of the carton and carried by said closure, said flap being disposed upon the interior of the carton and adjacent the upper portion of the opposite lateral wall, said last named lateral wall being weakened at its upper end to form a tab connected to the end wall section issuing therefrom and severable from said lateral wall to leave an opening in said lateral wall, said flap being weakened at a locality opposite said tab to form another tab connected to the end wall section from which said flap issues and severable therefrom, said tabs being capable of being jointly forced into the interior of the carton and adjacent the inner surface of the closure to facilitate grasping of the closure and severance of the same from the carton.

2. A carton constructed from sheet material and comprising lateral walls, a bottom connected with said lateral walls, end wall sections issuing outwardly from the ends of said lateral walls and being adapted to be folded over and secured together to form an end wall for the upper end of the carton, said carton being weakened to form a closure embodied in said end wall and severable from the carton, a flap formed on the end wall

section issuing from one of the lateral walls of the carton and carried by said closure, said flap being disposed upon the interior of the carton and adjacent the upper portion of the opposite lateral wall, said last named lateral wall being weakened at its upper end to form a tab connected to the end wall section issuing therefrom and severable from said lateral wall to leave an opening in said lateral wall, said flap being weakened at a locality opposite said tab to form another tab connected to the end wall section from which said flap issues and severable therefrom, said second named tab registering with said first named tab, said tabs being capable of being jointly forced into the interior of the carton and adjacent the inner surface of the closure to facilitate grasping of the closure and severance of the same from the carton.

3. A carton constructed from sheet material and comprising lateral walls, a bottom connected with said lateral walls, end wall sections issuing outwardly from the ends of said lateral walls and being adapted to be folded over and secured together to form an end wall for the upper end of the carton, said carton being weakened to form a closure embodied in said end wall and severable from the carton, a flap formed on the end wall section issuing from one of the lateral walls of the carton and carried by said closure, said flap being disposed upon the interior of the carton and adjacent the upper portion of the opposite lateral wall, said last named lateral wall being weakened at its upper end to form a tab connected to the end wall section issuing therefrom and severable from said lateral wall to leave an opening in said lateral wall, said flap being weakened at locality opposite said tab to form another tab connected to the end wall section from which said flap issues and severable therefrom, said second named tab being of the same shape as said first named tab and registering therewith, said tabs being capable of being jointly forced into the interior of the carton and adjacent the inner surface of the closure to facilitate

grasping of the closure and severance of the same from the carton.

4. A carton including lateral walls, an end wall section issuing from the end of one of the lateral walls, a flap formed on said end wall section and lying adjacent the inner surface of the opposite lateral wall and detached therefrom, an end wall section issuing from the end of the last named lateral wall and overlying said first named end wall section and secured thereto, other end wall sections issuing from the other lateral walls and secured to one of the previously referred to end wall sections to form a leak proof end wall for the carton, said carton being weakened to provide a severable closure in said end wall, said closure including said flap, and severable registering tabs formed in both said flap and in the lateral wall overlying said flap for facilitating detachment of said closure.
5. A carton including lateral walls, an end wall section issuing from the end of one of the lateral walls, a flap at right angles to said end wall section and lying adjacent the inner surface of the opposite lateral wall and detached therefrom, an end wall section issuing from the end of the last named lateral wall and overlying said first named end wall section and secured thereto, other end wall sections issuing from the other lateral walls and adhesively secured to one of said end wall sections, lines of weakening extending across said last named end wall sections near the ends of the lateral walls from which they issue, and a line of weakening at the fold line between the second named end wall section and the lateral wall from which it issues, said last named line of weakening extending into said lateral wall to form a severable tab connected to the second end wall section, said lines of weakening forming a severable closure in the end wall of the carton, said first named lines of weakening forming flanges underlying said closure, said flanges being unsecured to said first end wall section.

REYNOLDS GUYER.
